TRIPPING MECHANISM FOR OFFSET PRINTING MACHINES

Charles A. Harless, Riverside, Conn., and Burton C. Polglase, Jr., White Plains, N. Y., assignors to R. Hoe & Co., Inc., New York, N. Y., a corporation of New York

Application August 16, 1954, Serial No. 449,927

5 Claims. (Cl. 101—218)

This invention relates to tripping mechanism for printing machines, and more particularly for web offset printing machines.

It is an object of the invention to provide a tripping mechanism of simplified construction.

A further object is to provide such a mechanism incorporating also an impression adjustment.

A still further object is to provide improved arrangements for alternatively tripping a printing unit or selected components thereof.

With these objects and still other objects, which will appear in mind, mechanism embodying the invention in a preferred form will now be described with reference to the accompanying drawing, and the features forming the invention will then be pointed out in the appended claims.

In the drawing:

Fig. 1 is a schematic linkage diagram of the mechanism of the invention;

Fig. 2 is an enlarged detail view of the trip shaft mechanism, taken on the line 2—2 of Fig. 3;

Fig. 3 is a section on the line 3—3 of Fig. 2;

Fig. 4 is a detail section on the line 4—4 of Fig. 3;

Fig. 5 is a section on line 5—5 of Fig. 1, showing the motor drive arrangement; and

Fig. 6 is a detail view on line 6—6 of Fig. 5 showing an indexing arrangement.

The printing unit generally is of the type shown in Huck Patent 2,366,335, and in which two impressions are printed simultaneously on the two sides of a web W by a pair of blanket cylinders or offset printing cylinders, each serving as impression cylinder for the other. In the particular machine illustrated the web travels in a horizontal path and the two printing units, or two halves of the double printing unit, are superposed, one directly over the other. Front and back main frames support similar bearings for the various cylinders and rollers, although not shown herein.

The upper half of the unit comprises a blanket cylinder 10, a plate cylinder 11, ink motion form rollers 12, and ink drums 13 (generally called vibrators), for inking the form rollers. As will be understood, a further train of ink drums and rollers and an ink pump or fountain will form parts of the ink motion, supplying ink to the drums 13. These elements are known and since they form no part of the present invention, they will not be described herein. Further form rollers 14 forming part of a water motion also cooperate with the plate cylinder 11, as usual.

The lower half of the unit is similar to the upper half, and its construction and operation will be understood from the following description of the upper half.

The lower blanket cylinder 10' is carried in fixed bearings 16' while the upper blanket cylinder is carried in bearings 16 mounted in eccentric bushings 17, which are rotatable in the frames, so that the axial distance between cylinders 10 and 10' may be adjusted, for regulating the printing pressure and accommodating webs of different thicknesses, by a small angular movement of bushings 17.

2

Turning bushings 17 through a larger angle separates the cylinder 10 from cylinder 10' for tripping off the impression.

The bearings of plate cylinder 11 are carried in eccentric bushings 18, rotatable in the frames, for moving this cylinder in the vertical direction, as later described. Turning these bushings slightly, along with bushings 17, causes plate cylinder 11 to follow blanket cylinder 10 in its small adjusting movements, while turning bushings 18 through a larger angle separates cylinders 10 and 11, tripping the plate cylinder away from the blanket cylinder.

Further eccentric bushings 20 are rotatively carried by the eccentrics 18 of cylinder 11, and carry trip rings 22 for the ink motion. Poppet rod connections 24 to the form roller sockets or movable supports, provide for tripping the ink motion. Turning the bushings 20 causes a vertical bodily movement of rings 22 which, through the poppet rods 24 forces the form rollers 12 away from cylinder 11, thus tripping off the ink motion. In their movements toward and away from cylinder 11 these form rollers 12 swing about the vibrators 13, which rotate on fixed axes, as described in Harless and Polglase application, Serial No. 427,728, filed May 5, 1954, for Roller Socket Mounting, now Patent No. 2,818,805.

The mechanism for producing the required movements comprises trip shaft assemblies on both front and rear frames, together with suitable connecting arms or links, the tripping being accomplished by a rotary shaft movement and the impression adjustment by a bodily or translational movement of the shaft assemblies.

For clearness of illustration, the essential elements and their connections to the tripping eccentrics are shown in the form of a linkage diagram in Fig. 1, and the detailed construction of the essential parts is shown in the later figures.

In Fig. 1 there is indicated at A an arm pivotally supported at B upon a slidable block member 33. Links or connecting rods 40, 43 and 45 respectively, connect the eccentrics 17, 18 and 20 to arm A at points 42, 44 and 46, progressively further away from the pivot B. The linkage is shown in tripped on position, and the elements are tripped on by turning arm A counter-clockwise to the dotted line position A'. In the latter position, arm A and the links 40, 43 and 45 are all aligned together, and their points of attachment 40', 43' and 45' to eccentrics 17, 18 and 20 will have moved respectively to 41', 43' and 45' and be in alignment with the dotted line A'. It will be understood that the eccentrics 17, 18 and 20, the connecting rods 40, 43 and 45, the arm A and the slidable block B are duplicated on the opposite side of the machine from that shown in Fig. 1. Grooves 29 (Fig. 2), are cut in the frames to guide the slidable block members for movement along the line A'.

With the parts in "tripped on" position, the blocks 33 may be adjusted along the dotted line A' to raise or lower the upper blanket cylinder 10 with relation to the lower blanket cylinder 10', to regulate the impression pressure, or to provide for a change in the thickness of the paper to be printed without changing the distance between the axes of the cylinders 10 and 11, nor the relationship of the form rollers 12 to the cylinder 11.

By reason of the progressively longer crank arms for the links 40, 43 and 45, turning the arm A from tripped on (dotted line A') to tripped off (solid lines) position, moves the blanket cylinder 10, plate cylinder 11 and form rollers 12 through progressively greater distances, the result being to trip off the impression, plate and ink motion, separating these elements from their cooperating elements.

The trip shaft assembly (Figs. 2 and 3) comprises three concentric shaft elements 30, 31 and 32, for tripping, the ink motion, plate and blanket, respectively. These

shafts are indicated collectively as the pivot B in the schematic showing of Fig. 1. Shaft 30 is rotatively supported in bearings carried by blocks 33 slidably mounted on the machine frame structure, shaft 31 is rotatively supported on shaft 30 by bushings 34 and shaft 32 is rotatively supported on shaft 31 by bushings 35. The required rotary movements are imparted to the shafts through crank arm 36 fixed to shaft 32, connecting rod 37 and an arm or a bell crank which is driven as later described.

Trip shaft 32 connects to the eccentric bushing 17 through a connecting rod 40, pivotally connected to these two elements at 40', 42. The crank arm, or distance from point 42 to the axis of shaft 32 is short, as shown. Similarly shaft 31 connects to eccentric bushings 18 by a connecting rod 43, pivotally attached to the bushing and to a crank arm or plate 44 which is fixed to the shaft 31, and shaft 30 connects to the eccentric bushing 20 by a connecting rod 45 and crank arm or plate 46 fixed to shaft 30. The crank arms 42, 44, 46 are progressively larger, as shown. (They are indicated collectively as the arm A of Fig. 1.)

Crank plate elements 42, 44 and 46 are releasably coupled together by adjustable screw and slot connections. The outer shaft element 42 carries a coupling pin 52 passing into a bore 53 in the middle or intermediate shaft element 44. Similarly, intermediate shaft element 44 carries a coupling pin 50 passing into a bore 51 in the inner shaft element. By this means the shafts 30, 31 and 32 are coupled together in desired angular relationship, or may be released for separate movement.

Turning shaft 32 turns shafts 31 and 30, coupled to it, and through connecting links 40, 43, 45 turns the bushings 17, 18 and 20. The crank arms are so related to the eccentricities of the bushings as to produce progressively greater movements of the cylinder 10, cylinder 11 and form rollers 12 so that all elements are separated or tripped off.

The parts are so arranged that, in the tripped-on position, the connecting rods 40 and 43 and the common axis of shafts 30, 31 and 32 are aligned or coplanar, and the blocks 33 are guided in grooves 29 in the frame, as shown, to move along this same line or, in this same plane. (This is the line A' of the schematic Fig. 1.) The effect of a sliding adjustment of blocks 33 will therefore be to cause equal movement of the points of attachment of rods 40, 43 to their eccentricities. The parts are also so arranged that radii to these points of attachment make equal angles to the connecting rods (as shown, 90°) and the radii are equal in length. The eccentricities of bushings being also equal (or proportional to the radii, more generally) a movement of blocks 33 moves cylinders 10, 11 as a unit without disturbing their relation to each other. The parts are further arranged so that, in the tripped-on condition, connecting rod 45 for the ink motion is also aligned with, or coplanar with shafting 30—32 and the rods 40, 43, the connections of rods 43 and 45 to their eccentric bushings being substantially superposed. The result is to vary the impression without affecting the inking of the plate cylinder or the transfer of ink from plate to blanket cylinder.

The bodily adjustment of shafting 30—32 by shifting blocks 33 is accomplished by means of nuts or internally screw threaded members 60 (Figs. 2 and 3) receiving the threaded projections 61 of the blocks 33, and rotatively carried in the frame structure, as shown. Members 60 are externally formed with worm wheel teeth 61' engaging worms 62 carried on a shaft 63 journaled in the frames and rotated by a crank 64.

The mechanism for operating the tripping mechanism by rocking bell crank 38 about the stud or stub shaft 39 on which it is carried, comprises a link 70 connecting the other arm of the bell crank to a motor driven crank 71 carried by shaft 72. A link 70' serves to

operate similar tripping mechanism for the plate and ink motion of the lower half of the unit. This shaft 72 is driven through bevel gearing 73 from a shaft 74, which is driven through clutch elements 75, 76 by an electric motor reducer unit 77.

An indexing wheel 78 carries a tooth or projection 79 for engaging either of a pair of micro-switch operating arms 80, spaced 180° apart. The indexing wheel therefore stops the motor whenever the shaft 74 reaches either of two positions corresponding to tripped-on and tripped-off positions of the mechanism.

A pair of adjustable stops 81 (Fig. 2) are provided for limiting movement of the trip shaft in the tripped-on and tripped-off position, and the links 40, 43 and 45 are provided with the usual turn buckle adjustments. In initially setting up the equipment, the micro-switches 80 are adjusted to obtain a desired rocking movement of the trip shafts 30—32, and the stops 81 are set in the extreme positions of movement. By adjusting the links 40, 43 and 45, desired corresponding positions of the plate cylinder, blanket cylinder and form rollers are thus provided for. The stops 81 may now be backed off slightly, but will serve to limit manual movement of the parts.

As shown in Figs. 2 and 4, a cover plate 90, indicated in phantom in Fig. 2 is provided. This member is rotatably carried by a disc 91 mounted on a stub shaft 92. The cover plate 90 is shaped so as to accommodate the heads of coupling pins 50 and 52 when the latter are in the coupling position, of Fig. 4, but not to accommodate the heads of these pins when pulled out to uncouple either or both of the crank plates 42 and 44. As will be noted, notches 93 in the shanks of these pins cooperate with spring pressed ball detents to hold the pins in either coupling or uncoupling positions. Since the cover 90 cannot be swung down to the position of Fig. 2 if either pin 50 and 52 is pulled out the fact that this cover is in the downward position is assurance that the crank arms are coupled together. The position of the cover or guard 90 is used to insure that power operation of the tripping mechanism will not be attempted unless all the elements are properly coupled together. This result is achieved by forming disc 91 with a depression 95 which receives a roller 96 carried on the operating arm 97 of a micro-switch 98. Whenever the arm 97 is lifted, the power supply for the tripping motor 77 is interrupted, and an operating circuit is established when the disc 91 is in the position of Fig. 2. The tripping motor is preferably operated manually under normal conditions, but is arranged to trip off the impression automatically if the feeding of the web is interrupted.

Sockets such as are shown at 208 in the Huck Patent 2,366,335 are provided to receive a suitable bar for turning the shafts 30, 31 and 32 manually, and by manipulating the coupling pins 50 and 52, any of the shafts 55 may be operated separately when it is desired to make adjustments to the machine.

What is claimed is:

1. In a web offset printing machine, tripping mechanism comprising a trip shaft, crank means thereon comprising a crank arm, link and pivot connecting the same to the crank arm for tripping each of the impression, the plate and the ink motion, respectively, means mounting the trip shaft for aligning all the said links and the trip shaft axis in tripping-on position, the last said means comprising a block rotatably supporting the trip shaft, means for adjustably positioning the said block in the direction of alignment for varying the impression, and means for releasably coupling the said crank arms together for tripping the unit and for uncoupling the crank arms to trip the ink motion and plate separately.

2. In a web offset printing machine, tripping mechanism comprising a plurality of concentric trip shafts, a crank means on each shaft, links and pivots connecting them to the crank means for tripping the impression, the

plate and the ink motion, respectively, means mounting the trip shafts for aligning all the said links and the trip shaft axis in tripping-on position, the last said means comprising a block rotatably supporting the trip shafts, and means for adjustably positioning the said block in the direction of alignment for varying the impression, power means for rotating one of the trip shafts and releasable pin couplings connecting said shafts, whereby the plate, ink motion and impression may be tripped manually and separately as well as by power and together.

3. In a web offset printing machine, tripping mechanism comprising a trip shaft, crank means thereon, links and pivots connecting them to the crank means for tripping the impression, the plate and the ink motion, respectively, means mounting the trip shaft for aligning all the said links and the trip shaft axis in tripping-on position, the last said means comprising a block rotatably supporting the trip shaft and means for adjustably positioning the said block in the direction of alignment for varying the impression, and power means for rocking the trip shaft between predetermined tripping-on and tripping-off positions.

4. In a web offset printing machine, tripping mechanism comprising a trip shaft, crank means thereon, links and pivots connecting them to the crank means for tripping the impression, the plate and the ink motion, respectively, means mounting the trip shaft for aligning all the said links and the trip shaft axis in tripping-on position, the last said means comprising a block rotatably supporting the trip shaft and means for adjustably positioning the said block in the direction of alignment for varying the impression, and electric power means for rocking the trip shaft between predetermined tripping-on and tripping-off positions and indexing means for deenergizing the said electric power means in the said positions.

5. In an offset printing machine having a frame rotatably supporting first and second blanket cylinders between which a web is printed on both sides simultaneously, a plate cylinder co-acting with the first blanket cylinder and inking rollers co-acting with the plate cylinder, bearings in the frame to support the second blanket cylinder for rotation on a fixed axis, first eccentric bushings in the frame to support the first blanket cylinder for movement toward and away from the second blanket cylinder, second eccentric bushings in the frame to support the plate cylinder for movement toward and away from the first blanket cylinder, and third eccentric bushings associated with the second eccentric bushings to support the ink rollers for movement toward and away from the plate cylinder, and in combination, a pivoted arm device adapted to rotate the first, second and third eccentric bushings simultaneously for tripping the blanket and plate cylinders and the ink rollers, means operable to adjust the position of the pivot for the pivoted arm device to vary the distance between the axes of the blanket cylinders without changing the relative position of the plate cylinder and the first blanket cylinder, and means connecting the said pivoted arm device to the said eccentric bushings for effecting conjoint and equal movement of the said first blanket cylinder and the plate cylinder in response to adjustment of the position of the said pivot.
